UNITED STATES PATENT OFFICE.

JOHN S. HAUG, OF PHILADELPHIA, PENNSYLVANIA, ASSIGNOR TO THE U. G. I. CONTRACTING COMPANY, OF PHILADELPHIA, PENNSYLVANIA, A CORPORATION OF DELAWARE.

METHOD OF INTRODUCING A STEAM JET TO A WATER-GAS-GENERATOR FUEL BED.

Application filed September 17, 1921. Serial No. 501,309.

To all whom it may concern:

Be it known that I, JOHN S. HAUG, a citizen of the United States, residing at Philadelphia, in the county of Philadelphia and 5 State of Pennsylvania, have invented a new and useful Method of Introducing a Steam Jet to a Water-Gas-Generator Fuel Bed, of which the following is a specification.

It is present common practice to supply 10 steam in a straight flow or line jet admitted from the wall of the generator top space, and this straight jet of steam impinges either upon the fuel bed or upon the wall of the generator and is dispersed at either one of 15 these points and distribute itself more or less throughout the generator top space. The impact of such a straight jet or stream of steam is, however, very heavy and if it impinges upon the top of the fuel steam will be 20 forced in very heavy quantity through the fuel at the particular point of impact which results in excessive cooling of that part of the fuel and also in poor decomposition of the very heavy quantity of steam forced 25 through the fuel at this point. If the straight jet of steam impinges on the wall of the set there will be heavy cooling and a wearing effect or eroding upon the brick lining.

The principal object of the present invention 30 is to obviate the above mentioned defects and disadvantages and to effect an improvement in the supply of steam to water gas generators whereby the impact of a concentrated and very high velocity jet of steam 35 with either the fuel bed or the wall of the set is prevented. Another object of the invention is to introduce the steam in diffused and expanded form uniformly to the entire 40 surface of the fuel bed whereby water entrained in the steam is readily reevaporated and the steam advantageously applied.

Other objects of the invention will appear 45 from the following description and the invention may be said to consist in the method of introducing a steam jet in diffused and expanded form and uniformly to the entire 50 surface of a water gas generator fuel bed which consists in imparting a rotatory motion to the jet by discharging it tangentially upon a curved surface before it strikes the fuel bed, and this can be done either internally or externally of the generator wall as will 55 fully appear from the following explanation.

The invention also comprises the improvement to be presently described and finally claimed. 55

In the following description reference will be made to the accompanying drawing forming part hereof and in which 60

Figure 1 is a diagrammatic vertical sectional view illustrative of apparatus by means of which the invention can be practiced when rotatory motion is imparted to the jet outside of the generator wall. 65

Fig. 2 is a sectional view drawn to an enlarged scale and illustrating in elevation the curved wall shown in Figure 1.

Fig. 3 is a horizontal section on lines 3—3 of Fig. 2. 70

Fig. 4 is a vertical sectional view of apparatus by means of which the invention can be practiced when rotatory motion is imparted to the jet inside of the generator wall, or, more specifically, in the coal hole branch at 75 the top of the generator.

Fig. 5 is a horizontal sectional view of the same drawn to an enlarged scale, and

Fig. 6 is a horizontal sectional view of apparatus by means of which the invention 80 can be practiced when rotary motion is imparted to the jet inside of the generator wall.

Referring to Figs. 1-3, the steam jet entering at 1, is given a rotatory motion in a specially shaped fitting 2 which is shown in 85 those figures and which may be described as conchiform prior to its discharge into the generator, this rotatory motion being of course preserved or persisted in after the entry of the steam into the generator. In 90 the fitting 2 the jet of steam is discharged tangentially upon the curved wall 3 before it strikes the fuel bed and in fact before it enters the generator chamber. Referring to Figs. 4 and 5, the jet of steam is discharged 95 tangentially along the inner surface of the coal hole branch 4 of which the inner surface 5 is curved. Referring to Fig. 6, the jet of steam is discharged tangentially along the generator wall 6 which is curved. 100

The invention is more especially applicable to the supplying of steam to the top of the fuel bed for making a down run but it might be applied to the supplying of steam to the bottom of a generator fuel bed. However, as 105 stated, it is more applicable to the top of the fuel bed, among other reasons because a rose or spray nozzle or device at the top of

the fuel bed would undoubtedly burn off partly at least because the air blast is always upward. In the description use has been made of the term steam jet but the invention applies equally well if the term air jet be substituted for the term steam jet because the invention really consists in the described method of introducing a fluid jet to a water gas generator fuel bed and in fact both kinds of jets are employed, and the invention is applicable to both.

It will be obvious to those skilled in the art to which the invention relates that modifications may be made in details of procedure without departing from the spirit of the invention which is not limited as to such matters or otherwise than as the prior art and the appended claims may require.

I claim:

1. The method of introducing a steam jet 20 in diffused and expanded form and uniformly to the entire surface of a water gas generator fuel bed which consists in imparting a rotatory motion to the jet by discharging it tangentially upon and along a curved 25 surface before it strikes the fuel bed, substantially as described.

2. The method of introducing a fluid jet 30 in diffused form and uniformly to the entire surface of a water gas generator fuel bed which consists in imparting a rotatory motion to the jet by discharging it tangentially upon and along a curved surface before it strikes the fuel bed, substantially as described.

JOHN S. HAUG.
